FOREIGN PATENT DOCUMENTS

EP 0 89190 A2 7/1998

Primary Examiner—Mitchell Siegel

(74) Attorney, Agent, or Firm—Heller Ehrman White & McAuliffe

(57) **CLAIM**

The ornamental design for a golf club head, as shown and described.

DESCRIPTION

FIG. 1 is a front perspective view of a golf club head of the present invention;

FIG. 2 is a rear perspective view thereof;

FIG. 3 is a top plan view thereof;

FIG. 4 is front elevational view thereof;

FIG. 5 is a bottom plan view thereof;

FIG. 6 is a rear elevational view thereof; and,

FIG. 7 is a right-side elevational view thereof, the left side elevational view being a mirror image of the right-side elevational view.
